(57) **CLAIM**

The ornamental design for a buckle member, as shown and described.

DESCRIPTION

FIG. 1 is a perspective view of a buckle member showing the new design;

FIG. 2 is another perspective view of the buckle member according to the present invention;

FIG. 3 is a top plan view thereof;

FIG. 4 is a bottom plan view thereof;

FIG. 5 is a right side elevational view thereof;

FIG. 6 is a left side elevational view thereof;

FIG. 7 is an elevational view of one end thereof; and,

FIG. 8 is an elevational view of the opposite end thereof.

The broken line portions of the disclosure are for illustrative purposes only and form no part of the claimed design.
